UNITED STATES PATENT OFFICE.

GEORGE W. ENSINGER, OF ELM STATION, PENNSYLVANIA.

FURNACE.

SPECIFICATION forming part of Letters Patent No. 443,753, dated December 30, 1890.

Application filed May 5, 1890. Serial No. 350,602. (No model.)

To all whom it may concern:

Be it known that I, GEORGE W. ENSINGER, a citizen of the United States, residing at Elm Station, Lower Merion township, Montgomery

5 county, Pennsylvania, have invented an Improvement in Furnaces, of which the following is a specification.

My invention relates to furnaces of the type disclosed in sundry Letters Patent of the 10 United States granted to Edward Fales, dated May 18, 1886, and numbered respectively 342,080, 342,081, 342,082, and 342,083. The Fales furnace referred to embodies an open-topped fire pot or chamber provided with a 15 grated bottom, and disposed within and clear of the walls and above the bottom of the furnace proper, which latter is of considerably greater diameter than said pot. A second and annular grate exists within and radially 20 and circumferentially bridges the space between the exterior of the pot and the furnace wall, and is usually placed at an elevation somewhat above that of the grate within the fire pot. Heretofore the fire pot and the second grate, or that exterior to the pot, have been 25 together formed as a solid casting, and the exterior grate has been utilized to support the pot within the furnace by resting as to its outer rim upon a ledge or shoulder formed 30 upon the inner faces of the furnace wall. In practice the Fales grate has fallen short of its possibilities of usefulness in that it has been found, in cases where it is desired to place a Fales fire pot and grate in a completed 35 furnace to replace a grate of another construction, to be impossible to carry the fire pot and grates through the entrance to such furnace, and it has therefore been necessary to take down its wall. In cases, moreover, 40 where breakage of or damage to any portion of the grate has occurred, it has not been possible to replace simply the destroyed portion, but it has been necessary to sacrifice the entire grate.

45 It is the object of my invention to so construct a grate of the Fales type as to overcome these objections, and this object I accomplish by resort to a construction herein-after set forth, which, generally stated, consists in forming in sections, and in providing 50 with means for locking together, certain parts

which have heretofore been made as a rigid whole,—and in providing special devices to take the place of the second set of grate bars in supporting the fire pot.

55 In the drawings I illustrate, and herein I describe, a good form of a convenient embodiment of my invention, the particular subject-matter claimed as novel being hereinafter definitely specified.

60 In the drawings, Figure 1 is a central vertical sectional elevation of a furnace provided with a grate embodying my improvements. Fig. 2 is a top plan view of the grate removed from the furnace. Fig. 3 is a top plan view 65 of the fire pot, its supports, and the grate within the fire pot. Fig. 4 is a fragmentary detail of the lugs which support the fire pot grate.

Similar letters of reference indicate corresponding parts.

70 In the drawings, A is the furnace, the walls of which may be of any usual form or arrangement, and B is the ash door. The charging door, not shown, conveniently exists on the 75 side of the furnace nearest the eye in Fig. 1.

C is the fire pot, the same being, when mounted in the furnace, an open-topped receptacle of any desired dimensions, and being according to my invention formed in sections. 80 In the drawings I show said fire pot as being circular in plan, and as being formed or composite of four segmental sections, $c' c^2 c^3 c^4$, the lines of division between which are vertical. The component sections are laterally 85 joined to each other in any preferred manner to complete the wall of the fire pot. I find it convenient to provide each section with an outwardly projecting lug at or near each of its ends or lateral margins, and of these pairs 90 of lugs, which I respectively designate D D D and D' D' D' D', and which are preferably respectively cast integral with the section to which they respectively belong, I prefer to make one of each two, viz. D', sufficiently long 95 to act as a supporting arm. When then the sections are assembled to form the pot, one long and one short lug at each of the joints will be brought into registry with each other, and when said lugs are fastened together by 100 the bolts D^X, or otherwise, the pot will have become a rigid whole.

The meeting edges of the fire pot sections are, to effect a more close union, dovetailed or otherwise fitted into each other, being conveniently provided each at one edge with a tongue e and at the other edge with a groove e^x .

The fire pot grate F, which I hereinafter for convenience term the lower grate, may be supported within the fire pot in any preferred manner. It being, in the construction shown, 10 desired that the grate should be capable of being rocked, I provide it with two lateral studs $f f'$ and with a shaking handle or rod f^x , and also provide the lower portion of the fire pot with suitable bearings within which 15 said studs are entered. Each of these bearings are, as shown in Fig. 4, conveniently formed in lugs G which depend from the lower edge of the fire pot, and which lugs are conveniently vertically divided, the respective 20 halves appertaining to different adjacent sections of the pot.

The inner face of the furnace is provided with two supports or ledges, the lower one of which, H, I term the supporting ledge, and 25 the other one of which, H^x , I term the grate ledge.

The arms D', radiating from the exterior of the fire pot as hereinbefore explained, are of sufficient length to extend to and rest upon 30 the supporting ledge H, and by so doing maintain the fire-pot centrally within the furnace and above its floor.

The upper edge of the fire pot, which is about level with the ledge H^x of the drawings, embodies an external shoulder c^5 . To complete the furnace it is necessary to provide the second annular grate to cover the annular space between the pot and the walls. This grate, which is lettered J, is, according 35 to my invention, made in sections, of which four, respectively designated $j' j^2 j^3 j^4$ are shown in the drawings. Each section rests as to its outer edge upon the ledge H^x and as to its inner edge upon the shoulder c^5 , and 40 the adjacent ends of the sections, in meeting, simply abut against each other.

My improved grate, as is obvious, may, when breakage of any of its parts occurs, be repaired by merely substituting a new member in place of a broken one. It is also obvious that when it is desired to introduce the grate into a furnace the wall of which already exists, the members of my improved grate may be inserted one by one through the 45 furnace door and put together after all are within.

Having thus described my invention, I

claim and desire to secure by Letters Patent:—

1. In combination with an inclosing furnace 60 wall, a fire pot of less diameter than said inclosing furnace and supported within the same, a lower grate within the fire pot, and an upper grate surrounding the fire pot and detachable therefrom, substantially as set 65 forth.

2. In combination with an inclosing furnace wall, a sectional fire pot, a grate within the fire pot, means for supporting the fire pot within the furnace and above the floor thereof, 70 and a grate surrounding the fire pot, substantially as set forth.

3. In combination with an inclosing furnace wall, a sectional fire pot, means for supporting said fire pot above the bottom of the furnace, 75 a lower grate within the fire pot, and an upper grate formed in sections and surrounding the fire pot, substantially as set forth.

4. In combination with an inclosing furnace wall, a fire pot divided into sections, means 80 for uniting said sections, supporting arms extending from said sections, a grate within said fire pot, and a sectional grate extending from said fire pot to the inclosing furnace wall, substantially as set forth.

5. In combination with an inclosing furnace wall embodying internal ledges or supports, an open topped fire pot formed in sections, means for uniting said sections, supporting arms extending from said sections to a ledge, 90 and a sectional grate extending from the fire pot to a ledge, substantially as set forth.

6. In combination with an inclosing furnace wall embodying internal ledges or supports, an open topped fire pot formed of sections 95 each of which embodies an external lug and an external arm which reaches to the ledge of the wall, the lug and arm of each section being respectively in registry with adjoining arm and lug of the adjacent sections, means 100 for securing said meeting lugs and arms together, a shoulder formed upon the exterior of said fire pot, a grate supported within said fire pot, and a grate formed of sections which sections rest upon the exterior shoulder of the 105 pot and a ledge of the furnace wall, substantially as set forth.

In testimony that I claim the foregoing as my invention I have hereunto signed my name this 8th day of April, A. D. 1890.

GEORGE W. ENSINGER.
In presence of—

W. M. C. STRAWBRIDGE,
J. BONSALL TAYLOR.
